UNITED STATES PATENT OFFICE

103,067

DESIGN FOR A TEXTILE FABRIC

Joseph Mack, Passaic, N. J., assignor to Dazians,
Inc., New York, N. Y.

Application August 22, 1936, Serial No. 64,521

Term of patent 3½ years

To whom it may concern:

Be it known that I, Joseph Mack, a citizen of the United States, residing at Passaic, in the county of Essex and State of New Jersey, have invented a new, original, and ornamental Design for a Textile Fabric, of which the following is a specification, reference being had to the accompanying drawing, forming part thereof, wherein—

The figure is a plan view of a textile fabric showing my new design.

The unit of design consists of a single motif, but the design unit consists of two motifs arranged in reverse relation.

I claim:

The ornamental design for a textile fabric substantially as shown and described.

JOSEPH MACK.
